CLOSURE SEAL

Charles A. Mayer, Queens, N. Y.

Application October 21, 1938, Serial No. 236,356

2 Claims. (Cl. 298—7)

This invention appertains to new and useful improvements in seals and more particularly to means whereby the usual closure or gate of a coal truck chute can be sealed in a practical manner.

The principal object of the present invention is to provide a seal for coal truck chute gates which will permit the gate to be sealed in a manner preventing unauthorized lifting of the gate without affording detection.

Another important object of the invention is to provide a seal of the character stated which can be installed on present-day types of chute gates.

These and various other important objects and advantages of the invention will become apparent to the reader of the following specification.

In the drawings:

Figure 1 represents a fragmentary rear elevational view of a truck showing the chute and novel seal means.

Figure 2 is a sectional view taken substantially on the line 2—2 of Figure 1.

Figure 3 is a perspective view of the lower bracket.

Figure 4 is a perspective view of the upper bracket.

Figure 5 is a perspective view of the pin.

Figure 6 is a fragmentary detailed sectional view on the line 6—6 of Figure 1.

Figure 7 is a rear elevation of the gate and modified form of latch means.

Figure 8 is a fragmentary perspective view of the latch arm shown in Figure 7.

Referring to the drawings wherein like numerals designate like parts, it can be seen that numeral 5 represents the rear wall of a coal truck which has the vertically extending guides 6—6 for the chute gate 7. Numeral 8 denotes the chute which extends rearwardly from the truck and which has the vertically extending side walls 9 and 10.

In carrying out the present invention, a lower bracket A and an upper bracket B are employed and are shown in Figures 3 and 4, respectively.

The lower bracket A is L-shaped having the portion a apertured to receive securing means for attaching the bracket to the wall 9. This bracket A includes the right angularly disposed elongated portion b on which is the slider 13 which is provided with the horizontally disposed flange 14 terminating in the longitudinally extending barrel 15 through which the pin 16 is slidably disposed. The free end of the portion b

is bent backwardly to form the abutment or stop 17 for the slider 13.

Character reference B represents the upper bracket which has openings therein for receiving securing means 19 securing the bracket to the gate 7. The lower portion of this bracket B is bent outwardly to form the flange 20 which terminates in the barrel 21.

The relationship of the bracket B with respect to the bracket A is such as to result in the alignment of the barrel 21 with the barrel 15 when the flange 20 comes down to rest upon the elongated portion b of the bracket A.

With the barrels 21 and 15 thus aligned, the pin 16 can be disposed therethrough. The pin 16 has the head 22 at one end and adjacent this head 22 are the longitudinally spaced openings 23. At the other end portion of the pin 16 is the third opening 24. A tie wire or the like 25 can be trained through the opening 24 and through one of the openings 23 so that the ends of this wire 25 are disposed out in front of the bracket 12 where a seal button 26 can be pressed in place, uniting the terminals of the wire 25.

Thus persons either authorized or unauthorized must break the wire 25 before the pin 16 can be removed to permit elevation of the gate 7 and discharge of the coal from the truck.

With this seal in place the purchasing consumer can inspect the gate to determine whether the same has been ruptured preparatory to accepting the delivery.

A modified form of the invention is shown in Figure 7 wherein reference character 5a represents the rear of the coal truck on which are the vertical guides 6a—6a in which the gate 7a is slidable. The short chute is denoted by reference character 8a and includes the side walls 9a and 10a. The upper bracket 18a is of the same construction as the bracket 18 and the slider 13a is of the same construction as the slider 13. The pin 16a is used in the same capacity as the pin 16 in conjunction with the tie wire 25a and the seal 26a.

The modification resides solely in the lower bracket A and in the modification the bracket is denoted by reference character 12a. This bracket is divided into the plate section a' and the arm b'. The adjacent ends of the plate a' and the arm b' are provided with barrels 27 and 28, respectively. These barrels are aligned and have the pin 29 extending therethrough. Thus the arm b' and the plate a' are hingedly connected together and rivets or the like can be disposed through openings 30 in the plate a' to 55

secure the plate in position on the wall 9a. It can now be seen that when the gate 7a is opened the arm b' can be swung to a position against the wall 9a so that it will not interfere with the discharge of coal.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. In combination a dump truck body having a rearwardly disposed chute including side walls, a gate at the rear of the truck body complementary to the chute and being vertically slidable, an arm projecting inwardly from the side wall of the chute, a slider on the arm provided with

a horizontal barrel, a bracket on the end gate provided with a barrel adapted to be located in alignment with the barrel on the slider when the end gate is in closed position, and a pin for disposition through the aligned barrels. 5

2. In combination a dump truck body having a rearwardly disposed chute including side walls, a gate at the rear of the truck body complementary to the chute and being vertically slidable, an arm projecting inwardly from the side wall of the chute, a slider on the arm provided with a horizontal barrel, a bracket on the end gate provided with a barrel adapted to be located in alignment with the barrel on the slider when the end gate is in closed position, and a pin for disposition through the aligned barrels, and a hinged connection between the arm and the said side wall of the chute. 10 15

CHARLES A. MAYER.
